UNITED STATES PATENT OFFICE.

JOHN F. WARNER, OF MUNCIE, INDIANA.

PUMP.

1,079,308.

Specification of Letters Patent.

Patented Nov. 18, 1913.

Application filed January 29, 1912. Serial No. 674,022.

To all whom it may concern:

Be it known that I, JOHN F. WARNER, a citizen of the United States, residing at Muncie, in the county of Delaware and State 5 of Indiana, have invented certain new and useful Improvements in Pumps, of which the following is a specification.

This invention relates to improvements in pneumatic devices for the cleaning of car- 10 pets and like fabrics generally, and has especial reference to that class of machine comprising a cylinder, piston rod and piston, valves, and a dust receptacle and a mouthpiece; the said several parts being 15 so combined and arranged that by a reciprocatory moving of the cylinder, there is produced a continuous suction at the mouthpiece, the dust drawn from the surface over which the mouthpiece is moved, being 20 caught and retained in the receptacle.

The general object of this invention is to provide improvements in a machine of this class whereby increased efficiency may be had and maintained in the operating of the 25 same.

More specific purposes of the invention are to provide a cylinder and piston which will be simple and economical of construction, durable and not liable to get out of 30 order or repair, and which will be operable with slight friction and capable of being easily opened or taken apart for the purpose of cleaning same.

The above named and other purposes 35 which will become apparent as the nature of my invention is better understood, are accomplished by the new construction, combination and arrangement of parts de- 40 scribed in this specification, and defined in the appended claims, and illustrated in the accompanying drawings.

In the drawings the several parts of the invention, as they appear in the different views, are identified by similar characters 45 applied thereto.

Figure 1 is a side view of a cleaning machine in which my invention is embodied. Fig. 2 is a transverse sectional view taken on the line 2—2 in Fig. 1. Fig. 3 is an enlarged longitudinal vertical central sectional view of the main portion of the machine. Fig. 4 is a transverse sectional view taken on the line 4—4 and viewed in the direction indicated by the arrow 4 in Fig. 3. Fig. 5 50 is a transverse sectional view taken on the line 5—5 and viewed in the direction indicated by the arrow 5 in Fig. 3. Fig. 6 is a detailed view of the hinge joint between the members of the retention chamber. The cylinder A made of sheet metal of 60 suitable thickness has a smooth bore and its rims are outturned or flared as shown. On the tubular member shown and which constitutes one of the main elements of this machine, and which member is designated 65 as the piston tube B, is secured a piston head C provided with the packing ring C¹ made of rubber composition or other suitable material and which fits the bore of the cylinder. Blocks D and E secured on the piston tube 70 at each side of the piston head C are provided with openings D¹ and E¹ that register with openings of similar size in the wall of the piston tube. Flaps D² and E² made of leather or other suitable material are 75 secured to the blocks and constitute valve closures for the said openings D¹ and E¹. To constitute bearings for the piston tube and closures for the ends of the cylinder, and to perform additional functions which 80 will presently be referred to, cylinder heads of the peculiar construction shown herein, are provided. The lower head consists of a convex shaped plate F whose edge is curled inwardly and joined to the rim of 85 the cylinder by a soldered or hammered weld. Secured to this plate at the central opening F¹ therein is an annular ring F² having an inturned rim. A ring made of 90 felting or other suitable material such as a soft rubber composition, and stuffed into the annular opening between the ring and the piston tube, effectively closes the opening F¹. F³ and F⁴ designate holes in the plate F and whose functions will be pres- 95 ently referred to. A plate F⁴ designated as a valve plate and which has a central opening F⁵ is secured to the inner side of the head plate F. Between these plates is a 100 valve ring G made of soft material such as felt, and which fits snugly on the piston tube. The head plate H having a central opening H¹ and provided with a closure ring H² and stuffing ring whereby a bearing 105 for and closure is had at the upper end of the cylinder in the manner as just described for the lower head of the cylinder, has a plain peripheral edge as shown in Fig. 3. This plate H is provided with the holes H³ and H⁴. The valve plate H⁴ secured to the 110

head plate H and provided with the central opening H⁵ has an annular ledge which fits snugly in the bore of the cylinder.

To constitute means to bind the upper head plate of the cylinder to place, there is provided a member of the peculiar construction and arrangement shown plainly in Figs. 3 and 4. This member, designated as a head band, consists of a circular metallic band 10 L which is V-shaped in cross section the lips L¹ and L² being adapted to engage the rim of the cylinder and the rim of the head plate H respectively. The ears L³ are formed integral with the ends of the head 15 band, and in suitable holes therein a bolt M provided with a wing nut M¹ is disposed. This head band is sufficiently resilient that it may be expanded and slipped over the rim of the head plate H and the rim of the upper 20 end of the cylinder. By screwing down the wing nut M¹ the head band is constricted the rims being forced together and a closure of the cylinder effected. A handle L⁴ formed integral with the said head band 25 constitutes a grip or handle to be used by the operator in moving the cylinder reciprocatingly on the piston tube.

N designates the piston tube handle; its shank N¹ which is screwed into the bore of 30 the piston tube forms a substantial connection and at the same time constitutes an air tight closure of the upper end of the piston tube. This tubular member B with the several parts arranged and combined therewith 35 as shown is adapted to have communication with the surface to be cleaned. Such communication being established and a reciprocatory movement of the cylinder being had, the several parts perform the functions 40 to be presently described. The neck tube B¹ constitutes the terminal portion of the piston tube B and on its slightly tapered end may be easily attached a mouthpiece O having a standard form of shank O¹. This 45 mouthpiece may be one of a number of mouthpieces having various forms of base portions or mouths adapted to traverse fabrics of different textures and surfaces of various contour. Between the neck tube B¹ 50 and the said piston tube B, and into which both tubes have communication, is arranged a receptacle of the construction and which performs the function hereinafter referred to.

55 From the description thus far, the functions of the several parts are apparent, it being understood that suction is produced whenever the mouthpiece is at contact with the surface to be cleaned. With a downward 60 movement of the cylinder the valve ring G closes the opening F⁵ flap E² closes, and the air contents of the upper portion of the cylinder pass out through the opening H⁵ and the holes H³; at the same time flap D² will 65 have opened and the contents of the piston

tube B enter the lower portion of the cylinder. With upward movement of the cylinder the valve ring J closes the opening H⁵, flap D² closes, the contents of the lower portion of the cylinder pass out through the opening F⁵ and holes F³; at the same time flaps E² will have opened and the contents of piston tube B enter the upper portion of the cylinder. Thus by a reciprocatory moving of the cylinder a powerful and continuous suction is produced at the mouthpiece 70 and the cylinder contents are exhaled through the holes F³ and H³ of the lower and upper heads respectively. By the peculiar construction and arrangement of 75 parts constituting the cylinder heads, and of the rings G and J, there is such baffling of the cylinder contents and at the same time such opening and closing of the ends of the cylinder that while there is free exhalation 80 therefrom, escapement of dust is rendered practically impossible.

For the purpose of preventing the entry 85 into the piston tube of dust and particles of grit and dirt sucked through the mouthpiece, and also to afford facility for the retention of such dirt and dust for the purpose of ultimately disposing of same, a retention 90 chamber of the construction shown herein is arranged between the piston tube B and the neck tube B¹. This retention chamber, designated as a dust receptacle, consists of members constructed and separably connected 95 combined and arranged as shown in Figs. 1 and 3. The upper member P cone shaped 100 in form and made of cast or sheet metal has its neck P¹ secured to the lower end of the piston tube. In the circular mouth of this member P is disposed a union ring Q that has a peripheral tongue Q¹ and the peripheral faces of the ring proper are slightly beveled as shown. The cone shaped dust bag R made of canvas or other suitable textile material has its mouth edging secured to the internal face of the union ring by 105 cementing or riveting. The lower member or funnel S of this dust receptacle also is funnel shaped and is of the elongated form as shown. The neck tube B¹ which projects through the lower end of this funnel S has its upper portion secured to the wall of the funnel in the manner as shown in Fig. 1 by 110 soldering or riveting and whereby it is held and braced securely in place.

To provide stiffness and rigidity of the 115 mouth of the funnel S so that practicable connection thereof to the union ring Q may be had and a joining thereof to the upper member P may be effected, the rim of the said funnel S is curled over a ring S¹ made 120 of stout wire and which is of proper diameter to fit freely on the union ring Q. It will be seen that when the union ring is set into engagement with the mouth of member P 125 and the mouth of member S is brought to 130

engagement with the face of the lower side of the union ring, that a drawing toward each other of said members will cause them to tighten on the said union ring.

5 P² designates a latch consisting of a stout spring having its upper portion secured to the wall of the member P and whose free end is of form to engage the mouth rim of the funnel S and to normally hold same securely in place.

10 P³ designates a hinge member secured on the member P and which detachably engages a complementary hinge member S³ secured on the side and near the edge of the funnel S.

15 T designates a disk shaped sheet of metallic netting adapted to fit removably inside the union ring and at the mouth of the dust bag. The peak of the cone shaped dust bag, U as shown in Fig. 3, is secured to a central portion of the said netting by a hook or clip V which has an ear V¹.

20 In practising the invention the debris from the surface being traversed, including the coarser particles of dirt and dust are caught by the netting and caused to accumulate in the funnel S, there being ample room in said funnel and the neck tube B¹ being adjacent the upper wall free action of the suction therethrough is not impeded. The 25 dust contents passing the netting is caught and retained in the dust bag. Such slight amount of dust as may pass the dust bag is prevented from being exhaled from the cylinder by the operation of the several parts 30 and in the manner hereinbefore described.

35 To gain access to the interior of the cylinder the head band is loosened and the head plate H is removed; the piston tube may then be drawn upwardly until the piston 40 head is clear of the upper end of the cylinder.

What I claim as my invention and desire to secure by Letters Patent is:—

1. In a machine of the kind described, the 45 combination of a piston tube having a pair of openings in the wall thereof, a closure for one end of the piston tube, a piston head secured on the piston tube at location between the said openings, valves for the said openings, a cylinder capable of being reciprocated on the piston head having its rims flanged, heads to close the end of the cylinder, the head for the lower end of the cylinder being secured thereto, and the said heads

55 being provided with openings therein and with stuffing boxes for the piston tube, a valve plate secured to the interior side of each of the cylinder heads and having a central opening of diameter larger than that of the piston tube, a ring slidingly disposed 60 on the piston tube between each head and its valve plate and adapted to close the opening in the valve plate, an expansible member to coengage the flange of the cylinder and the rim of the last named head and that is capable 65 of being constricted whereby the said cylinder flange and the rim of the head may be drawn and held securely together.

2. A pump of the kind described comprising a piston tube having a pair of openings 70 in the wall thereof, a piston head secured on the piston tube at location between the said openings, a valve for each of said openings, a cylinder capable of being reciprocated on the piston head, heads to close the ends of 75 the cylinder and which are provided with closed bearings for the piston tube, one of said heads being removable, a valve in each of the said heads, and an expansible member to coengage the end of the cylinder and the 80 rim of the removable head and that is capable of being constricted whereby the said head may be drawn and held securely to the end of the cylinder.

3. A pump comprising a cylinder having 85 its rims flanged, heads for the ends of the cylinder, the head for one end of the cylinder being secured thereto, and each of the said heads being provided with openings therein and with stuffing box for the piston, 90 a valve plate secured to the interior side of each of said heads and having a central opening of diameter larger than that of the piston tube, a ring between each head and its valve plate and which is of diameter 95 slightly smaller than said central opening, and an expansible member to coengage the flange of the cylinder and the rim of the head plate and that is capable of being constricted whereby the said cylinder flange and the 100 said head may be drawn and held securely together.

In testimony whereof I affix my signature in presence of two witnesses.

JOHN F. WARNER.
